SELF-LOCKING KNIFE SHEATH

Fred H. Gibson, Eureka, Calif.

Application April 20, 1951, Serial No. 222,133

4 Claims. (Cl. 30—151)

1

This invention relates to knife sheaths and more particularly to a knife scabbard or sheath of the self-locking type which is carried by a belt worn by the user of the knife in the manner of the conventional sporting knife and sheath.

Sportsmen such, for example, as hunters and fishermen, and particularly fishermen engaged in the commercial fishing industry, need to have a knife of the single blade type readily at hand at all times, and sometimes in a moments notice, and therefore must rely on some means of holding the knife in an open position in the sheath and in a manner to prevent the knife from falling out of the sheath.

Various prior art devices and methods, such as a combination knife and sheath having a locking latch, have been employed to keep the knife in place in the sheath but these devices require a knife specially designed for the purpose. The service condition of the conventional leather scabbard depends on the wet or dry condition of the weather and considerable skill is required, at times, to remove the knife from the scabbard without causing excessive pulling on the belt or trousers. Where the conventional snap and strap is employed to hold the knife in the scabbard this means is usually regarded as too uncertain to rely on its always being fastened at the proper times.

After duly considering the foregoing problem, it has occurred to me that what is essential and is desired is a sheath which has provision for receiving any conventional single blade knife of reasonable size and further provision for establishing an absolute hold on the knife in the scabbard at such times as is desired to lock the knife therein and for releasing the knife in the sheath at such other times when it is desired to use the knife; the sheath at such other times producing no drag on the knife whereby the same may be inserted within or withdrawn from the sheath time and again without experiencing any drag or pull on the knife.

It is an object of the present invention therefore to provide a new and improved self-locking sheath which does not require a specially made knife.

Another object is to provide a sheath having provision for establishing an absolute hold on the knife merely in response to applying sufficient pressure on the knife while in the sheath to move the same fully therein to a releasable locking position.

A further object is to provide a sheath of the self-locking type having provision for releasing

2

the knife within the sheath upon manipulation of a simple lever carried by the sheath.

Still another object resides in the provision of a self-locking sheath which produces no drag or pull on the knife upon replacement thereof within the sheath at such times as the sheath is unlocked.

Still other objects, advantages and features of the present invention will become more fully apparent from the following description of a preferred embodiment thereof which is illustrated in the accompanying drawings to which reference is had in the description and wherein:

Figure 1 is a front view in elevation of the sheath of the present invention with the knife shown locked therein;

Figure 2 is a sectional view of the knife and sheath illustrated in Figure 1 as seen along the line 2—2 thereof;

Figure 3 is a side elevational view of the knife and sheath illustrated in Figure 1;

Figure 4 is a fragmentary sectional view of the knife and sheath taken along the line 4—4 thereof;

Figure 5 is a sectional view taken along the line 5—5 of Figure 4;

Figure 6 is a fragmentary sectional view taken along the line 6—6 of Figure 4;

Figure 7 is a fragmentary sectional view of the knife and sheath similar to Figure 4 but showing the knife in the released position within the sheath;

Figure 8 is a sectional view taken along the line 8—8 of Figure 7;

Figure 9 is a top view of the sheath as seen along the line 9—9 of Figure 7, the knife appearing in section;

Figure 10 is a sectional view taken along the line 10—10;

Figure 11 is a perspective view of the locking lever;

Figure 12 is a top view of the locking lever;

Figure 13 is a detail view in perspective of the locking spring; and

Figure 14 is a fragmentary view in perspective of the sheath, certain portions being broken away to illustrate the construction thereof.

Referring now to the drawings for a more complete understanding of the invention, 20 designates a single blade knife having a hilt 21, a blade 22, and a handle 23. In Figures 1 to 10 the knife is shown carried by the sheath 24 of the present invention, being inserted therein in the locking position in Figures 1 to 6 and in the released position in Figures 7 to 10.

The sheath 24 comprises a main housing or casing 25 which may be made of metal, plastic or leather and carries at the top thereof a casing piece 26 which may be made of metal or plastic and which has a reduced collar portion 27 which is received as at 28 in matching engagement within the opening in the upper end of the main casing 25. On one side of the casing piece 26, the casing 25 extends in overlapping relation therewith by the casing portion 29 which has integrally formed therewith the flap 30 for receiving a belt.

The casing piece 26 houses the locking lever generally designated 31 and a spring 32 formed of suitable material such as spring steel for yieldably urging the locking lever to the right side of the casing piece as viewed, for example, in Figures 1 and 4.

The locking lever 31 may be formed of metal or plastic and has a U-shaped portion 33 defining a channel 34 into which the cutting edge portion of the blade 22 is loosely received. Lever portion 33 also comprises a semi-circular notch 35 into which the rounded portion 36 of spring 32 is pivotally received, the flat portion 37 of the spring being pressed in face adjacency with inner surface 38 of the casing piece 26.

Lever portion 33 also preferably comprises a rounded upwardly extending projection 39 which engages the underside of the hilt 21 when the knife is lowered into the sheath.

One leg of the U-shaped lever portion has a somewhat narrowed extension 40 which terminates in a lever handle 41 which extends outwardly of casing piece 26 through an opening 42 formed therein. Handle 41 has a rounded projection 43 which moves into a notch 44 therefore formed in casing piece 26 when the locking lever is rocked about the spring 32 to the knife release position as may best be seen in Figure 7. When the locking lever is rocked about spring 32 to the locking position, as best appears in Figure 4, the spring being compressed by this movement, projection 43 rides on the surface 45 of casing piece 26 until the lower extremity of the lever handle 41 moves adjacent to the surface 46 of the casing piece 26, it being understood, however, that actual engagement therewith occurs only when there is no knife in the sheath.

When the knife is retained in released position within the sheath, it is guided along the back edge thereof by the surface 47 of the locking lever, this surface being opposite to the channel opening 34 and spaced sufficiently from the bottom of the channel so as to loosely accommodate reasonably sized knife blades of different widths.

The narrowed leg portion 40 of the locking lever has a rounded projection 48 which extends upwardly into engagement with the underside of the hilt and, thus, when the knife is inserted into the sheath in the released condition, it is supported therein by the hilt being in engagement with projections 39 and 43 of locking lever 31. When pressure is applied to the knife, the hilt being in engagement with lever projection 48, the lever is pivoted downwardly about spring 32 and lever projection 43 is moved outwardly of notch 44 which causes the spring to be compressed. Thus, when projection 43 engages surface 45 of casing piece 26, the energy stored in the spring causes the projection 43 to be cammed along surface 45 until the back edge of the knife blade 22 is forced against the surfaces 49 and 50 of casing piece 26, the cutting edge of the knife blade being engaged by the side surface 51 of lever projection 39 whereby the knife blade is firmly engaged at the 75

three points 49, 50 and 51 and an absolute hold on the knife in the sheath is thus established.

When it is desired to release this hold on the knife, the handle 23 is grasped with the four fingers of the hand and the lever handle 41 is pressed inwardly and upwardly with the thumb whereupon the lever projection 43 is cammed upwardly along the casing piece surface 45 until the projection 43 drops into the notch 44 to thereby release the knife. Lever handle 41 preferably is rounded and formed as illustrated to facilitate this release operation and to project a minimum amount beyond the side of the sheath thereby adding only slightly to the overall width thereof.

From the foregoing it should now be apparent that a self-locking sheath has been provided which meets the requirements of the aforesigned objects of the invention and while one form only of the invention has been described in detail herein, it will be understood by those skilled in the art to which it pertains that modifications and changes in structure may be resorted to without departing from the spirit and scope of the invention as set forth in the appended claims.

What I claim as my invention is:

1. In a self-locking sheath for a conventional sporting knife, the combination of a releasable locking lever including means engageable with one edge of a knife blade inserted in the sheath for moving the other edge of the blade against an inner side surface of the sheath, and spring means interposed between the opposite side surface of the sheath and said means for urging the same in the direction of said first named side surface when said lever is moved inwardly of the sheath, said lever comprising an upwardly extending projection engageable with the underside of the hilt of the knife whereby the lever is moved inwardly of the sheath when the knife is fully forced therewith, said lever including a handle portion extending laterally outwardly of the sheath for moving said means in the direction of said opposite side surface of the sheath to release the knife therein when said handle portion is pressed by the thumb while the fingers of the hand grasp the handle of the knife.

2. In a self-locking sheath for a conventional sporting knife, the combination of a sheath casing, a locking lever disposed within the upper portion of said sheath and having an opening therein for loosely passing the blade of said knife therethrough and into the sheath, a leaf spring having end portions disposed against an inner side surface of said sheath casing and having a rounded central portion for pivotally engaging said lever, said sheath casing having a notch in the opposite side surface thereof and an opening in said opposite side, said lever having a projection receivable in said notch and having a handle portion extended through said side opening, said side opening comprising a cam surface extending from said notch and said projection being cammed along said cam surface under power of energy stored in said spring when the projection is forced outwardly of the notch whereby the knife blade is urged by the lever into locked engagement against said opposite side surface of the sheath casing, said lever having an upwardly extending portion adjacent said projection and engageable with the underside of the hilt of the knife for forcing said projection out of the notch when pressure is applied to the extending portion sufficiently to force the same fully within the sheath casing, said handle portion being movable inwardly and upwardly of

the casing sheath by pressure of the thumb thereon to return said projection into the notch when the fingers of the hand grasp the handle of the knife.

3. In a self-locking sheath for a conventional sporting knife, the combination of a sheath casing, a casing piece secured to the upper end of said sheath casing and having an opening in the side thereof, a locking lever disposed within said casing piece and having a thumb engaging portion extended through said opening, said thumb engaging portion having a surface for engaging one edge of a knife blade inserted in the sheath, said lever having a U-shaped portion defining a channel for receiving the other edge portion of said knife blade therewithin, a leaf spring interposed between said U-shaped lever portion and the side surface of said casing piece disposed oppositely from said side thereof, said U-shaped portion having a rounded notch therein and said spring having a rounded portion pivotally received within said notch, said side of the casing piece having a notch on the inner surface thereof adjacent the upper edge of said opening therein, said thumb engaging portion having a projection receivable in said last named notch, said lever having an upwardly extending projection disposed intermediate said U-portion and said thumb engaging portion and engageable with the underside of the hilt of the knife whereby said projection on the thumb engaging portion is moved out of the notch therefor and into said opening, said U-shaped portion is moved by said spring into engagement with said other edge portion of the knife blade, and said one edge of the knife blade being forced into locking engagement with said inner surface of said side of the casing piece having said opening therein when the knife blade is forced fully into the sheath casing, said thumb engaging portion being movable by the thumb to pivot the lever about said spring as a pivot

10

15

20

25

35

40

to return said projection on the lever thumb portion to said notch therefor while the handle of the knife is grasped by the fingers of the hand.

4. In a self-locking sheath for a conventional single blade sporting knife, the combination of a sheath casing, a spring disposed within said casing, lever means disposed within the casing in pivotal engagement with said spring and urged thereby to one side of the casing, said side of the casing having a notch therein and an opening therethrough, said lever means having a projection receivable in said notch and movable into said opening when forced out of said notch, said lever means having a surface engageable with one edge of a knife blade inserted in said casing for urging the other edge of the blade into locking engagement with the side surface of the casing adjacent said opening therein when said projection moves into the opening, means on said lever means and engageable with the hilt of the knife for moving said projection outwardly of the notch when the knife blade is forced fully within the casing, and a lever extension of said lever means extended through said opening and engageable by the thumb while the fingers grasp the handle of the knife for moving said projection back into said notch thereby to release the knife blade in the sheath casing.
